Attorneys

UNITED STATES PATENT OFFICE.

FREDERICK P. HAYLES, OF ROCKVILLE CENTER, NEW YORK.

RAILROAD SPIKE.

Application filed September 19, 1923. Serial No. 663,673.

To all whom it may concern:

Be it known that I, FREDERICK P. HAYLES, a citizen of the United States, residing at Rockville Center, Long Island, in the county of Nassau and State of New York, have invented a new and useful Railroad Spike, of which the following is a specification.

This invention relates to railway track construction, and aims to provide novel means for locking the spikes employed for securing the rails and tie plate together, the tie plate cooperating with the locking means to insure against accidental displacement thereof.

Another important object of the invention is to provide a lock of this character which may be readily and easily positioned, eliminating the necessity of making changes in the usual tie plate and tie construction to install the same.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a sectional view through a rail and fastening spike constructed in accordance with the invention.

Figure 2 is a perspective view of the spike.

Figure 3 is a perspective view of the locking pin employed in connection with the spike.

Referring to the drawing in detail, the reference character 5 designates a railway tie which is of the usual and well known construction, and on which the tie plate is positioned.

The tie plate is formed of metal, and provides a rest for the rail 7, to protect the tie 5 and eliminate any possibility of the rail digging into the tie to weaken the same.

Formed in the tie plate 6 are the usual spike openings, through which the spikes pass, when positioned on a tie, the spike in the present showing being indicated at 8.

As shown, the spike, which forms an important feature of the invention is formed with the usual head 9 that contacts with the base of the rail associated therewith to secure the rail in position.

Formed in one of the surfaces of the spike is a longitudinal groove 10 that extends from the head 9, to a point an appreciable distance from the head as clearly shown by Figure 1 of the drawing. The rear wall of the groove 10 is disposed at an oblique angle, at the lower end thereof, providing an inclined wall 11 presenting a cam surface to bend the pin 12 positioned in the groove. It will be noted that the inclined wall 11 of the groove lies in such relation with the edge 13 of the spike opening in the tie plate that the pin 12 which is driven into the groove bends at an oblique angle adjacent to the edge 13 to lock the spike against accidental displacement.

It might be further stated that the pin 12 is formed of suitable metal, so that the spike will bend readily when the beveled end thereof contacts with the inclined wall of the spike. To insure the bending action of the pin 12, one end thereof is beveled at 14 whereby the beveled end will be deflected laterally when driven into the spike.

I claim:

1. A rail fastening device including a tie plate having a spike opening, a spike positioned in the opening, said spike having a groove formed in one edge thereof, an inclined wall formed at the lower end of the groove, a locking pin adapted to be positioned in the groove, said locking pin adapted to extend laterally when driven into the groove, and said locking pin being of a thickness equal to the space between the inclined wall and adjacent edge of the spike opening of the tie plate.

2. In a rail fastening device, a tie plate having a spike opening, a spike adapted to extend into the spike opening, said spike having a groove formed along one edge thereof, said groove having an end wall extending at an oblique angle with respect to the side walls thereof, and a locking pin adapted to be driven into the groove and extended laterally by its contact with the angular wall of the groove.

3. In a rail fastening device, the combination of a tie plate having a spike opening,

a spike extended into the opening, said spike having a groove formed with an inclined end wall, a locking pin adapted to extend into the groove and move laterally by contact with the inclined wall, and said spike adapted to engage the adjacent lower edge of the spike opening.

In testimony that I claim the foregoing as my own, I have hereto affixed my signature in the presence of two witnesses.

FREDERICK P. HAYLES.

Witnesses:

JOSEPH L. ROUSSEAU,
RAYMOND D. SIMONS.
